CLAIM

The ornamental design for a kids modular couch, as shown and described.

DESCRIPTION

FIG. 1 is a top perspective view of a kids modular couch, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view showing the kids modular couch in a fully disassembled state;

FIG. 10 is a front perspective view of an alternate configuration, using nineteen (19) components of the kids modular couch shown in FIG. 9;

FIG. 11 is a front perspective view of another alternate configuration, using seven (7) components of the kids modular couch shown in FIG. 9;

FIG. 12 is a front perspective view of another alternate configuration, using twelve (12) components of the kids modular couch shown in FIG. 9;

FIG. 13 is a front perspective view of another alternate configuration, using fourteen (14) components of the kids modular couch shown in FIG. 9;

FIG. 14 is a front perspective view of another alternate configuration, using seven (7) components of the kids modular couch shown in FIG. 9; and,

FIG. 15 is a front perspective view of another alternate configuration, using ten (10) components of the kids modular couch shown in FIG. 9.

The broken lines in the drawings illustrate environmental structure and forms no part of the claimed design.

1 Claim, 15 Drawing Sheets
